P. A. HÜNERMANN

INSULATING TUBE

Filed Sept. 28, 1926

FIG. 1.

FIG. 2.

FIG. 4.

FIG. 3.

UNITED STATES PATENT OFFICE.

PETER ADOLF HÜNERMANN, OF BERLIN-WEISSENSEE, GERMANY, ASSIGNOR TO THE FIRM JAROSLAW'S ERSTE GLIMMERWARENFABRIK IN BERLIN, OF BERLIN-WEISSENSEE, GERMANY.

INSULATING TUBE.

Application filed September 28, 1926, Serial No. 138,245, and in Germany May 14, 1925.

My invention refers to insulating tubes of the kind which are formed by winding webs of paper or other insulating material coated with a binder and having a considerable width around a rotating mandrel. In the manufacture of such tubes their length is limited by the width of the webs available for this purpose. If it is desired to manufacture long tubes, several such webs must be wound around the mandrel in juxtaposition and the difficulty arises of connecting the abutting edges of the wound-up webs and of sealing the joints between them in such manner that the insulating capacity at the joints is not materially inferior to the insulating capacity of the other parts of the insulator.

In order to obviate these drawbacks, it has been suggested to arrange the webs with their adjoining marginal portions overlapping each other, a cutter arranged near the mandrel cutting both webs through at the overlapping portions in such manner that the webs about to be wound upon the mandrel closely abut against each other with the adjoining cutting edges. However, insulators manufactured in this manner are still deficient in that the joint thus obtained between the two wound-up webs has the form of a plain annular gap which although being filled up with the lacquer or other insulating coating covering the paper still possesses an insulating capacity which is inferior to that of the other portions of the insulator, the cellulose of the paper being far superior in this respect to all lacquers, resins or other insulating coatings.

In the insulator according to the present invention the difference of insulating capacity is altogether avoided by forming the two abutting sections in such manner that their engaging ends have the form of concentric rings of conical section and stepped surface, whereby the gap which separates the two sections has a cross section bordered by a zigzag line and is closed in radial direction by the adjoining layers of paper so that the inferior insulating capacity at the joints as compared with the total radial section is so insignificant as to be altogether negligible.

Even if the several adjoining layers are staggered only so little that the joints of adjoining layers communicate with each other, the insulating capacity will still be far superior to that of a plain annular joint in as

much as the path offered to the current is greatly lengthened.

However, in a preferred embodiment of this invention the several layers are staggered to such an extent that the dielectric resistance of the zigzag path formed by the joint is great enough to withstand the pressure necessary for a radial passage of current across each layer. A staggered displacement of 5 mms. between adjoining layers will suffice in ordinary cases.

In order to produce insulators such as above described, I prefer leading the two adjoining webs with their marginal portions overlapping each other, as above described, and at the same time I cause the cutter severing these portions of the two webs to be laterally displaced during the cutting operation in such manner that the overlapping portions are cut through in an undulating line whereby the engaging ends of the two abutting sections are formed with stepped concentric rings of conical section.

In the drawings affixed to this specification and forming part thereof an insulator according to the present invention and the manner of making same is illustrated diagrammatically by way of example.

In the drawings

Fig. 1 is an axial section of the tube, showing the abutting ends of the two sections of the tube with the zigzag line bordering the cross sections of their ends.

Fig. 2 is a perspective end view of one of the two sections, and

Fig. 3 is an elevation, partly in axial section, of the mandrel, the two overlapping webs and the cutter severing them during manufacture.

Fig. 4 is a diagram showing means for displacing the cutter.

In the drawings 1 is the mandrel supported and set rotating in any suitable manner and 2 and 3 are the two webs which shall be wound upon the mandrel. As shown in the drawings the marginal portions of the two webs overlap each other and directly before being wound up are cut through by means of a cutter 4 of some well known kind which is mounted on a threaded spindle 5 running in threaded bearings 6 for lateral displacement in both directions in parallel to the mandrel, whereby the cutter is displaced for instance 5 mms. to the left during one revolution of the mandrel. After the cutter has been thus

displaced several times in one direction, its movement is reversed, the cutter being now displaced to the right, and so forth until the insulator is finished. If it is shown for instance that the cutter is capable of travelling 50 mms. to the left and 50 mms. to the right from its normal position, a reversal of the movement of the cutter will take place only after 20 windings and joints having the same radial position will occur only after 20 windings so that the insulating capacity is not in the least impaired.

Fig. 1 shows the zigzag line 7 bordering the cross sections of the butting ends of the two wound-up webs and Fig. 2 shows the concentric rings 8 of conical section which are thus interlocked.

I wish it to be understood that I do not desire to be limited to the exact details of construction shown and described, for obvious modifications will occur to a person skilled in the art.

I claim:—

1. Insulating tube consisting of a spirally wound sheet of insulating material and comprising two adjoining sections, each consisting of closely adjoining layers of insulating material, the engaging ends of said sections having the form of concentric rings of conical section.

2. Insulating tube consisting of a spirally wound sheet of insulating material and comprising two adjoining sections, each consisting of closely adjoining layers of insulating material, the engaging ends of said sections having conical surfaces stepped in spirals.

3. Insulating tube consisting of a spirally wound sheet of insulating material and comprising two adjoining sections, the engaging ends of said sections having axial sections bordered by a zigzag line.

4. Insulating tube consisting of a spirally wound sheet of insulating material and comprising two adjoining sections, the engaging ends of said sections having the form of stepped concentric rings of conical section.

5. Insulating tube comprising two adjoining sections, each consisting of closely adjoining layers of insulating material, a binder between adjoining spiral layers, the engaging ends of said sections having the form of concentric rings of conical section.

6. Insulator comprising a plain tube formed of spiral layers of a sheet of insulating material, said tube being subdivided transversely by a narrow gap of zigzag shaped cross-section.

In testimony whereof I affix my signature.

PETER ADOLF HÜNERMANN.
